UNITED STATES PATENT OFFICE.

WILLIAM STOFFEL, OF MCHENRY, ILLINOIS.

CYLINDER-COCK.

SPECIFICATION forming part of Letters Patent No. 350,276, dated October 5, 1886.

Application filed April 6, 1886. Serial No. 197,954. (No model.)

To all whom it may concern:

Be it known that I, WILLIAM STOFFEL, of McHenry, in the county of McHenry and State of Illinois, have invented a new and Improved 5 Cylinder-Cock Attachment, of which the following is a full, clear, and exact description.

My invention relates to the construction of an apparatus applicable for use in connection with the steam-cylinders of a locomotive or 10 other form of engine, the object of the invention being to provide an attachment whereby the water of condensation may be automatically discharged from the cylinder at each stroke of the piston, the apparatus, however, 15 being so arranged that it may be set to open both valves at once or to close both valves at once; and the invention consists of certain novel constructions and combinations of parts to be hereinafter described, and specifically 20 pointed out in the claims.

Reference is to be had to the accompanying drawings, forming a part of this specification, in which similar figures of reference indicate corresponding parts in all the figures.

25 Figure 1 is a side view of a portion of a cylinder provided with my improved attachment, the valve-chambers being broken away and shown in central section to disclose the construction of the parts. Fig. 2 is a plan view of 30 the attachment, the view being taken on line *x x* of Fig. 1, certain portions of the attachment being shown in section. Fig. 3 is a detail view in partial section, illustrating the construction of one of the valve-plugs and its connection; and Fig. 4 is a sectional view taken 35 on line *y y* of Fig. 2.

In the drawings above referred to, *A* represents the cylinder of a locomotive-engine, beneath which there are arranged two valve-chambers, *B B*, connection between the cylinder and the valve-chambers being established 40 by means of tubes *a a*. These valve-chambers *B B* are each provided with inwardly-extending brackets *b b*, in which there is loosely 45 mounted a rod, *c*, the rear end of which is pivotally connected to the lower end of a lever, *C*, the upper end of said lever being provided with a connecting-rod, *d*, which extends backward to a position within reach of the engineer, the lever *C* being fulcrumed at *e*, as indicated. The rod *d* is provided with three

notches, arranged as indicated, and designated by the numerals 1 2 3, and the parts are so arranged that each of these notches may be brought into engagement with a stop, *t*, located 55 at any convenient fixed point.

In the valve-chambers *B*, I arrange plug-valves *D*, the stems of which project outward through appropriate openings formed in the rear ends of the valve-chambers, the seats of 60 the valves being inclined, as indicated at *i i*, and in the incline which constitutes the seat of the plug-valves *D* there are formed apertures *n n*, through which the water of condensation entering the valve-chambers will be discharged, 65 the valves *D* being arranged so as to fit loosely within the chamber. The extending ends of the valve-stems *f* are held within apertures *g*, that are formed in the forward ends of cylinders *G*, said cylinders being adjustably connected to rods *N N'*, said rods being in turn pivotally connected to a rocker, *P*, that is carried by the arm *H*, said arm being clamped to the rod *c* by means of a plate, *h*, that is held to the arm *H* by means of a bolt or set-screw, *l*, 70 this construction being best shown in Fig. 4, where it will be seen that the arm *H* and plate *h* are formed with two or more sets of recesses, so that the position of the rocker *P* may be adjusted either toward or from the rod *c*, as 75 the circumstances of the case require. The valve-stems *f* are held within the socket *g* by means of bolts or set screws *m*, which fit within apertures formed in the valve-stems and pass through the cylinders *G*, the apertures in 80 the valve-stems being enlarged in order to permit of a slight play, so that the valves may be properly seated in operation. Connection between the cylinders *G* and the rods *N N'* is established by means of the clamping-yoke *I*, a 85 set-screw, *o*, and a wedge, *L*, interposed between the rod and the cylinder, as best shown in Fig. 3, the inner face of the yoke opposite the wedge being inclined to correspond with the inclined face of the wedge, the idea being 90 to give an appropriate direction to the rod *N* or *N'*, said rods being set at a slight angle, as indicated in Fig. 2.

In operation we will suppose the steam to have entered in front of the piston within the 95 cylinder *A*, and this steam would have entered the forward valve-chamber through its tube *a*,

and would have forced the valve B of the said forward valve-chamber against its seat, and as the valve of the forward valve-chamber moved to its seat the rocker P would have been thrown in the direction of the arrow shown in Fig. 1, and in so moving would have carried the rod N in the direction of the arrow shown in connection therewith, thus moving the valve of the rear valve-chamber away from its seat to open a free passage for the water of condensation that was behind the piston in the cylinder A, the opening n in the rear valve-chamber at this time allowing for the passage of the water. When steam enters behind the piston in the cylinder A, the valve-plug D of the rear valve-chamber will in turn be forced against its seat, thus moving the connecting parts in a direction opposite to that above described, so as to carry the valve D of the forward valve-chamber away from its seat, so as to allow for the outward passage of the water of condensation from in front of the cylinder A. If the engineer desires to close both of the valve-chambers at the same time, he can do so by moving the rod d backward so that the stop with which it engages will enter the first notch formed in said bar or rod, for it will be seen that the movement of the rod d just described will move the rod c forward in the direction of the arrow shown in connection therewith in Fig. 1, and this movement will carry both of the valve-plugs to their seat. On the other hand, if the engineer desires to open both of the valve-cylinders at the same time, he can move the rod d so that the stop will be in engagement with the third notch in the rod, which movement of the rod d will carry both valve-plugs over from their seats.

Having thus fully described my invention, what I claim as new, and desire to secure by Letters Patent, is—

1. The combination, with two valve-chambers and their valve-plugs, of a rocker carried by an arm that is secured to a sliding rod, and connections between the rocker and valve-stems, substantially as described. 15

2. The combination, with two valve-chambers and their valve-plugs, said plugs being provided with stems, cylinders G, in which the valve-stems are seated, clamps I, connecting rods N N', a rocker, P, an arm, H, a sliding rod, c, a lever, C, and a connecting-rod, d, substantially as described. 50

3. The combination, with two valve-chambers and their valve-plugs, of cylinders G, in which the stems of the valves are seated, clamps I, rods N N', a rocker, P, carried by an arm, H, a rod, c, to which the arm H is clamped, a lever, C, a connecting-rod, d, formed with notches, and a stop, T, substantially as described. 55

4. The combination, with a cylinder, of two valve-chambers in connection with the ends of said cylinder, and provided with outlets, plugs closing the said outlets and having outwardly extending stems, a longitudinally-movable rod, a rocker carried by said rod, and connections between the ends of said rocker and the plug-stems, as set forth. 60 65

WILLIAM STOFFEL.
